JESSE P. OUTCALT, OF LANCASTER, OHIO.

Letters Patent No. 74,932, dated February 25, 1868.

IMPROVEMENT IN BALLOT-BOXES.

The Schedule referred to in these Letters Patent and making part of the same.

TO ALL WHOM IT MAY CONCERN:

Be it known that I, JESSE P. OUTCALT, of Lancaster, in the county of Fairfield, and State of Ohio, have invented a new and useful Improvement in Ballot-Boxes; and I do hereby declare the following to be a full, clear, and exact description of the same, reference being had to the accompanying drawing, making a part of this specification, in which—

Figure 1 represents a side elevation of my improved ballot-box, the side of the box or case enclosing the same removed for the purpose of showing the internal arrangement and construction; and

Figure 2 is a similar rear end elevation.

Similar letters of reference denote corresponding parts in both figures.

My invention consists, first, in the provision or employment of a double spiral hopper, arranged in such manner as to keep the balls separate, and to convey them to their tumblers in a continuous flow; second, in the employment of a crescent-shaped tumbler, by which the balls are taken separately from the hopper and deposited in the drawer or receptacle underneath; and, third, in the arrangement of the spring-trigger or retractor, by which the tumbler is operated as hereinafter set forth.

In the accompanying drawings, A represents an outer case or box, made in this instance of a rectangular form, but which may be made in any desired or suitable form, and of any suitable material, provided with the bottom, B, and with the sliding cover or top, C. D is an inner frame or box, of any suitable construction, around which, and between which and the outer frame, A, are arranged two series of spiral flanges or ledges, a b, arranged in such manner as to form the two spiral ways or flues c d running from opposite sides of the top of box D around said box, and terminating in upright discharge-passages or outlets, as shown at e f, fig. 2. The upper surface of the inner box, D, is divided by a diagonal rib or ridge, from which, as a centre, the surface is inclined downward in opposite directions, communicating with the opposite flues c d, starting from opposite sides of said box in such manner as to form suitable hoppers or receptacles communicating each with its appropriate spiral flues. At a convenient point in the vertical passages or outlets e f are two crescent-shaped tumblers E E', one in each outlet-passage, closing the same, and adapted, by the concave or pocket formed therein, to receive and retain one of the balls g or g'; g, for example, representing the white ball, and g' the black. The crescent-shaped tumblers are mounted or hung upon a central pivot or pivots, upon or with which they are free to turn each independently of the other, and are provided on their lower surface or side with a projecting pin or lever, h, to which one end of a link or connecting-rod, i, is attached, the opposite or front end of which rod i is connected to a slide F in the manner represented in fig. 1. The slides F are mounted in suitable parallel ways on the horizontal partition G, and have connected to them in any suitable manner (see figs. 1 and 2) one end of a spring, H, the opposite end of which is connected to the partition G, or it may be connected to any other suitable stationary point in the box, and which may be of any desired construction, so arranged as to hold the slides in the position represented by the drawings, except when acted upon by some extraneous force. I is a drawer, arranged in the bottom of the box A, underneath partition G, to receive the balls from the spiral hopper when discharged by the rotation of the tumblers, and A' is an opening in the front of the box, through which either or both the slides are reached and the tumblers operated for discharging the balls from their respective hoppers. The front of the box or case may be marked upon opposite sides of the aperture A' with painted or inlaid representations of a white and a black ball, to indicate the slides, by the operation of which a ball of the desired and corresponding color is discharged.

The operation is as follows: The person desiring to deposit either a white or black ball or ballot inserts his hand through opening A' in the outer case A, and, noting upon which side the balls of the desired color are located, by means of the painted representations on the front of the case, operates or draws forward the slide upon that side of the box, and thereby, through pitman i, rotates the corresponding tumbler, and discharges one ball of the desired color into the box or drawer I. The tumblers are so formed as to receive but a single ball, and the pocket therein should correspond in depth pretty nearly to the diameter of the balls employed, so that a continuation of outer curved line of the crescent-shaped tumbler in the completion of the circle will nearly or quite embrace within it the ball lying in the pocket or recess formed therein.

By this arrangement it will be seen that but a single ball can be discharged by the forward movement of

the slide, the form of the tumbler being such as to present an effectual barrier to the balls in the hopper whenever said tumbler is operated. The slides are provided with sockets, lips, or thumb-pieces, in any convenient manner, to facilitate their operation or forward movement, and the moment the finger is withdrawn, the spring H causes them to resume their former position, shown by the drawings, to receive another ball.

By the construction and arrangement shown, it will be seen that it will be a matter of impossibility for any person except the operator or voter to form any idea of the vote or color of ballot cast, as the opening or aperture in which the hand is inserted to cast such ballot need only be just large enough to admit the hand or the fingers; and when the hand is thus inserted, either slide may be operated and either color of ball deposited, at the option of the operator.

It will be obvious that the form of the box or tumbler may be varied from rectangular to cylindrical or octagonal, or from crescent-shaped to polygonal; that the construction and arrangement of the spring and slide may be varied; the action of the spring upon the tumbler may be reversed, if desired, in such manner that the tumbler may be moved into proper position to receive the ball by the operator, while the action of the spring in retracting the slide will cause its discharge; and that the machine, as a whole, may be made of any desired dimensions or capacity without departing from my invention; but the construction and arrangement described constitute an economical and effective one, and one, it is believed, that will be found to accomplish the desired end in a satisfactory manner.

Having now described my improvements in ballot-boxes, what I claim, and desire to secure by Letters Patent, is—

1. The double spiral hopper, by which the balls are kept separate and conveyed to the tumblers in the manner described.
2. The crescent-shaped tumblers, by means of which the balls are taken separately from the hopper and deposited in the drawer as set forth.
3. The spring H, in combination with the slide, and tumbler for retracting the same, as set forth.

JESSE P. OUTCALT.
